UNITED STATES PATENT OFFICE.

DAVID MCALLISTER, OF ALLEGHENY, PENNSYLVANIA.

SELTZOGENE.

SPECIFICATION forming part of Letters Patent No. 590,582, dated September 28, 1897.

Application filed January 9, 1897. Serial No. 618,623. (No model.)

To all whom it may concern:

Be it known that I, DAVID MCALLISTER, a citizen of the United States, residing at Allegheny, in the county of Allegheny and State 5 of Pennsylvania, have invented certain new and useful Improvements in Seltzogenes; and I do declare the following to be a full, clear, and exact description of the invention, such as will enable others skilled in the art to which 10 it appertains to make and use the same.

My invention has relation to improvements in the construction of seltzogenes or gazogenes for making and dispensing carbonated beverages, and the object is to simplify the 15 construction of the same.

To this end the novelty consists in the construction, combination, and arrangement of the same, as will be hereinafter more fully described; and particularly pointed out in the 20 claim.

The drawing is a vertical section of a seltzogene embodying my invention.

1 represents the water-receptacle, which is preferably globular in shape and provided 25 with a horizontal base 2 and an externally-threaded cylindrical neck 3.

4 represents a cylindrical metallic sleeve formed with an internal annular flange 5, the interior of said sleeve being threaded above 30 and below the flange 5, as shown.

6 represents the gas-generating chamber, which is formed with a cylindrical shank 7, externally threaded to receive the sleeve 4. The upper end of this chamber is provided 35 with an externally-threaded neck 8, to which is removably secured the cap 9. This cap is provided with a central screw-threaded orifice 10, which receives the threaded nipple 12 of the gooseneck 13, which is provided with an 40 ordinary plug-cock 14. The lower threaded end of the nipple 12 extends below the top of the cap 9 to receive a threaded sleeve 15, the converging lower end of which receives the flaring end 16 of a tube 17, which extends 45 downward to a point near the bottom of the receptacle 1.

18 represents a tube encompassing a portion of the upper end of the tube 17, its flanged end 19 being supported between the upper 50 face of the neck 3 of the water-receptacle 1 and the annular flange 5 of the sleeve 4.

The receptacle 1 is first filled with water and the sleeve 4 secured in place, with the tube 18 and gas-generating chamber adjusted in position to form a gas-tight joint between 55 said receptacle and the gas-chamber. The salts, usually consisting of an acid and an alkali, are now thoroughly mixed in powdered form and placed in the gas-chamber 6 on the outside of the tube 18, which of course must 60 be perfectly dry before the salts are inserted.

The cap, with the gooseneck and tube 17, is then secured in place, and the gazogene is ready for operation, and whenever a carbonated beverage is desired the gazogene is tilted 65 so that a portion of the water in the receptacle 1 flows through the tube 18 into the chamber 6 and mixes with the salts, thereby generating a gas and charging the water in the receptacle 1. When the cock 14 is opened, the 70 charged water is delivered through the gooseneck as desired for use.

The simplicity, convenience, and portability of my improved gazogene are apparent, and the facility with which it can be taken 75 apart and assembled as well as broken parts replaced is such as to commend it to general household use.

In addition to producing a carbonated beverage the various mineral-water salts—such as kissengen, vichy, the lithias, and the like—may be combined with the water to form an effervescent mineral water corresponding to the salt employed.

While I prefer to make my improved gazogene or seltzogene of transparent glass, it is obvious that colored or opaque glass, porcelain, earthenware, or block-tin may be used in its construction and the water-receptacle and gas-chamber covered with wicker or wire 85 work, as is customary in this class of articles.

Although I have specifically described the construction and relative arrangement of the several elements of my invention, I do not desire to be confined to the same, as such changes 95 or modifications may be made as clearly fall within the scope of my invention without departing from the spirit thereof.

Having thus fully described my invention, what I claim, and desire to secure by Letters 100 Patent, is—

A portable gazogene, comprising a water-

receptacle provided with an integral externally-threaded neck, a cylindrical internally-threaded sleeve 4 provided with an internal annular flange 5, a gas-generating chamber 5 removably secured to said water-receptacle, in combination with the removable screw-cap 9, the gooseneck 13 provided with the cock 14, and having a threaded nipple 12 by means of which said gooseneck is detachably secured 10 to said cap, and the tube 17 removably se-

cured to the lower end of said nipple by the internally-threaded sleeve 15, substantially as shown and described.

In testimony whereof I hereunto affix my signature in presence of two witnesses.

DAVID McALLISTER.
